UNITED STATES PATENT OFFICE

CHARLES J. HENSCHEL, OF RUTHERFORD, NEW JERSEY

DESIGN FOR A SIGNALING INSTRUMENT

Application filed January 21, 1932. Serial No. 42,580. Term of patent 7 years.

To all whom it may concern:

Be it known that I, CHARLES J. HENSCHEL, a citizen of the United States, and resident of Rutherford, in the county of Bergen and State of New Jersey, have invented a new, original, and ornamental Design for a Signaling Instrument, of which the following is a specification, reference being had to the accompanying drawing, forming part thereof.

Figure 1 is a front elevation and Figure 2

is a side view of a signaling instrument showing my new design.

I claim:

The ornamental design for a signaling instrument, as shown.

Signed at New York city, in the county of New York and State of New York, this 20th day of January, A. D. 1932.

CHARLES J. HENSCHEL.
